TYPE SLUG LOW SLUGGER

Charles W. Curle, San Francisco, Theodore C. Curle, Ross, and Ray F. Newton, San Francisco, Calif.

Application October 31, 1941, Serial No. 417,347

7 Claims. (Cl. 90—16)

The present invention relates to a machine for low slugging type slugs and particularly to a machine for effecting low slugging automatically as the slug passes through a channel or chute after it has been discharged from the line casting machine in which it is formed.

Slugs issuing from a line casting machine have type characters formed along their upper edges. The type thus formed is arranged in groups often spaced apart or from the ends of the slug, exposing flat areas of the slug of considerable length. When these flat areas exceed a given length they permit bulging of the paper during printing and thus often cause offsetting or smudging of that portion of the paper which should remain unprinted. It is customary therefore to cut away the slug in the long spaces between type to insure against offsetting thereby during printing. As the slugs issue in rapid succession from the line casting machine, it is desirable to accomplish this cutting away, or low slugging, as it is termed, rapidly and by a machine which is controlled automatically by the passage of the slug itself to cut the proper portions.

It is the object therefore of the present invention to provide a machine to effect accurate and efficient low slugging controlled automatically by the type slug being cut.

A further object is the provision in such a machine of an improved trip mechanism actuated by engagement of type on the slug to advance and retract the cutter and to provide a delay mechanism for preventing advancing of the cutter after the type passes the trip but before it passes the cutter.

A further object of the invention is the provision of a novel time delay mechanism for interposition between two mechanical movements.

Still further objects are the provision in a low slugger of novel means for adjusting the depth of its cut and means controllable by hand for rendering the cutter inoperative.

One form of the invention is illustrated in the accompanying drawings and further of its objects and advantages are made apparent in the following specification wherein detailed reference is made to the drawings.

In the drawings—

Fig. 1 is a vertical section on line I—I of Fig. 3, of a machine embodying the present invention, the pivoted armature shown in Fig. 3 being removed to expose other mechanism;

Fig. 2 is an enlarged detail view of the control mechanism shown in Fig. 1, with some of the parts removed and some broken away;

Fig. 3 is a sectional view on line III—III of Fig. 1; and

Fig. 4 is a sectional view on line IV—IV of Fig. 1.

5 The low slugger of the present invention is illustrated in the drawings as contained in a housing 10 which is rigidly supported by means not shown over a chute 11 down which the slugs pass after they leave the line casting machine, and preferably after they have been subjected to a side trimming operation. One such slug is shown at 12 as being urged downwardly through the chute 11 by a pusher 13. The construction of the chute 11 and manner of operation of the pusher 13 which advances the slug through it are clearly set forth in our co-pending application entitled "Type slug side trimmer," filed October 31, 1941, Serial No. 417,346.

10 A rotary cutter 14 intercepts and cuts away the upper edge of the slug 12 as it is advanced down the chute, and continues this cutting or low slugging until it approaches the type which projects upwardly from the slug as shown at 15. At this time a roller 16 carried by a trip bar 17 engages 15 and is raised by the type to swing the trip bar upwardly and actuate the mechanism which retracts the cutter. The cutter remains retracted until the roller drops off of the type and then returns to its cutting position after a delay of 20 time sufficient to permit the type to pass clear of its cutting edge so that the final cut serves to eliminate that portion of the slug indicated by the dotted line 18.

15 The cutter 14 which is cup-shaped is mounted on the end of a shaft 20 and enclosed, except for its forward edge, by a guard 21 depending from the housing 10. The shaft 20 is slidably mounted in a tubular shaft 22 and keyed against rotation therein by a pair of keys 23 which project from the shaft 20 into slots 24 in the lower end of the tubular shaft to serve as sliding keyways and thus permit retraction of the shaft 20 while it rotates. The lower end of the tubular shaft is journaled in a bearing 25 and the upper end of the cutter shaft 20 is journaled in a bearing 26. This upper bearing is supported in a sleeve 27 which is slidably mounted in a lug 28 formed interiorly of the housing 10 and bored for the reception of the sleeve. A nut 29 retains the bearing 26 on the shaft and holds it against a collar 30 which rests against a shoulder on the shaft, as shown. A spring 31 disposed between the upper end of the tubular shaft 22 and the collar 30 urges the cutter shaft 20 together with its bearing assembly and the sleeve 27 toward its re-

tracted position. Retraction under influence of the spring 31 is however limited by a screw 32 the head of which engages in a slot formed in a flange 33 which projects outwardly from the upper end of the sleeve 27. A gear 34 for driving the cutter is threaded to the exterior of the tubular shaft 22 from its lower end and its position on the shaft is fixed by a pair of pins 35 projecting from the shaft and shouldered at their outer ends to form stops for the hub of the gear. A sleeve 36 which projects from the housing of the bearing 25 extends to a point between the inner threaded surface of the gear and a reduced portion of the shaft 22. The clearance between the exterior of the sleeve and the threads on the interior of the gear is very small so that any lubricant tending to escape from within the housing toward the bearing 25 is worked back by the action of the threads during rotation of the gear around the sleeve. Likewise the upper end of the shaft 22 is threaded and extends into the sleeve 27 with the same result in preventing the loss of lubricant along the shaft 20.

Normally the cutter is held in its advanced or down position by the screw 32, the lower end of which is threaded through a cylindrical nut 38 in the free end of a lever 39, the opposite end of which is pivotally supported by a shoulder screw 40. The lever 39 is latched in its down position by a control cam 41 (see Fig. 2) which is mounted on a shaft 42 through the medium of roller bearings 43 which permit relative rotary movement of the shaft and cam. The normal position of the cam 41 is that illustrated in Fig. 2 with its lower end retaining the lever 39 down. Movement of the cam in a counterclockwise direction about the center of the shaft 42 causes a cam shoulder 44 on the cam to pass a cam shoulder 45 on the lever. This permits the lever and the cutter assembly to move upwardly under influence of the spring 31. Clockwise movement of the cam returns it to the position illustrated and swings the lever 39 downwardly through the action of the cam shoulders 44 and 45. Thus through the screw 32 which serves as a connecting link the cutter is returned to its cutting position.

The depth of cut may be regulated by adjustment of the screw in its threaded connection with the nut 38. In order to hold the screw against accidental rotation away from its adjusted position the under side of its head is bevelled as at 48 on two sides which rest against complementary bevels 49 on the sides of the slot in which it is retained. Consequently the screw may be rotated and retained by spring pressure in positions 180° apart. By this means the depth of cut made by the cutter can be set at increments equal to one half the pitch of the thread on the screw 32. A removable plate 50 on the housing 10 provides access to the head of the screw for effecting adjustment thereof.

As the slug 12 approaches the cutter which is normally advanced its forward edge is cut away as shown in Fig. 1. When the raised type 15 engages the trip bar 16 the latter is swung about its pivotal support 52 to lower its outer end 53 and an adjusting screw 54 carried thereby. This screw engages the actuating pin 56 of a micro switch generally indicated at 57. The switch, which is of conventional construction and therefore not illustrated in detail herein, is normally held open by a spring 58 which engages and urges a tail 59 of the trip bar 17 upwardly. When the trip bar rides up on the type 15 the switch is per-

mitted to close and complete a circuit to an electromagnet 60, shown in Fig. 3, the armature 61 of which is pivoted at 62. A non-magnetic spring 63 carried by the armature assists in breaking 5 contact when the circuit is opened.

When the electromagnet is energized the armature 61 swings on its pivot to raise a roller 64 carried by its lower end and thus to swing upwardly a lever 65 which, as shown in Fig. 1, is 10 pivoted on the shoulder screw 40. A link 66 is connected by a pin and slot 67 at its lower end to the lever 65 and by a pin 68 to a pawl 69 (see Figs. 1 and 2) at its upper end. The pawl 69 is pivoted at 70 and urged downwardly by a spring 15 71 into latching engagement with a shoulder 72 formed on the upper end of the control cam 41. Through these connections energization of the electromagnet, which occurs upon raising of the trip bar 17 when it is engaged by the type on the 20 slug, permits the control cam 41 to swing in a counterclockwise direction to effect retraction of the cutter to a position where the slug can pass below it without injury to the type face. A contractile spring 73, shown in Figs. 2 and 3, is fixed by a pin 74 to the control cam and by a pin 75 to the housing and urges the cam to move in a counterclockwise direction when it is released by the pawl 69. This movement of the cam is limited by a stop lug 76 which is cast integrally with the wall of the housing 10.

After the type 15 on the slug passes from beneath the trip bar 17 the cutter must be advanced to its cutting position by clockwise movement of the control cam. This return of the cutter must however be delayed until the type has cleared to a position where it will not be engaged by the advancing cutter. In order to effect delayed return of the control cam 41 it carries a pawl 78 pivoted to it by a pin 79 and engageable with a ratchet disc 80 which is fixed to the end of the shaft 42 and continuously rotated thereby at a relatively slow rate of speed by drive mechanism hereinafter described. The pawl 78 is urged toward engagement with the ratchet disc by a spring 81 but normally retained out of such engagement by an elevator lever 82 urged upwardly by a stronger spring 83 into contact with a pin 84 projecting forwardly from the side of the pawl. This elevator lever 82 pivots on the shoulder screw 40 and has a tail 85 which stops against the pin 75.

The pawl 78 is also connected by a link 86 with the lever 65 through the pin 84 at the upper end of the link and a pin and slot connection 87 at its lower end. Through this latter connection the pawl is positively held in its raised position when the link 65 swings upwardly, and the pin 87 at the lower end of link 86 is brought into axial alignment with the shaft 42 upon which the control cam rocks so that rocking of the cam does not in itself alter the position of the pawl.

Now assuming the control cam to have been released and to have moved counterclockwise to its position of rest against the stop 76, in which position the cutter is retracted, the pawl 78 is held clear of the rotating ratchet only by the link 86. When the trip bar leaves the type the magnet is de-energized and the lever 65 swings downwardly and allows the pawl to engage one of the teeth of the slowly rotating ratchet disc 80. The ratchet disc, through the pawl, returns the control cam to normal position and during its return the cam shoulders 44 and 45 act to return the lever 39 and, through the link screw 32, to advance the cutter assembly. The speed of the

ratchet disc is, however, sufficiently slow to effect advancement of the cutter only after the slug has moved sufficient distance safely to clear the type 15.

During the final portion of the return movement of the control cam, a tail 90 on the pawl 78 engages a stop lug 91 and throws the pawl out of engagement with the ratchet disc. At this time the pin 84 on the pawl has come into engagement with the elevator lever 82 which holds the pawl away from the ratchet teeth. The control cam is again retained against counterclockwise movement by the epring pressed pawl 69.

It is desirable in some instances to eliminate the low slugging operation on the slugs which are passing through the chute 11. Means are therefore provided to retract and retain the cutter in its retracted position by hand. These means comprise a plunger 93 extending through the housing and fitted with a knob 93' by means of which it may be reciprocated by hand. The lower end of the plunger is connected with a link 94 which is in turn connected by a pin and slot 95 with the lever 65. This makes it possible to raise the lever 65 by hand and thus retract the cutter by release of the control cam in the manner described above. The plunger 93 carries a spring clip 96 which acts as a detent with a collar 97, on a stationary tube 98 through which the plunger slides, to retain the plunger in either its raised or lowered position.

The drive and power transmission for the mechanisms herein described are illustrated in Figs. 3 and 4. Power from a suitable source is received by a bevel gear 100 disposed exteriorly of the housing and transmitted by a shaft (not shown) which extends through a bearing box 101 to a main drive gear 102 fixed to the inner end of the shaft. The gear 102 meshes with an intermediate gear 103 pinned to a counter shaft 104 mounted for rotation in bearings 105 and 106. The gear 103 meshes with the gear 34 (see also Fig. 1) which drives the cutter shaft. To drive the ratchet disc 80 which returns the cutter control cam with delayed action, the counter shaft 104 carries a worm 108 which meshes with a worm gear 109, shown in dotted lines in Fig. 4 and also shown in Fig. 3, as keyed to a shaft 110 which rotates in bearings 111 and 112. This shaft 110 also carries a small gear 113 meshing with a larger gear 114 which is keyed to and drives the shaft 42 which rotates in bearings 115 and 116 and which, as previously described, carries the ratchet disc 80 at its end. The reduction effected by the worm and worm gear together with the gears 113 and 114 times the ratchet disc at the speed required to effect the necessary time delay in returning the cutter to its advanced position after the trip bar has left the type and opened the circuit to the electromagnet.

Having thus described our invention, what we claim and desire to secure by Letters Patent is:

1. In a low slugger for type slugs, a cutter, resilient means urging the cutter to retracted position, latch means normally latching the cutter in advanced position, and trip means in advance of the cutter and engageable by type on the slug to release said latch means, said trip means including a switch, an electromagnet controlled thereby and a time delay mechanism

controlled by the electromagnet to prevent interception of the type by the cutter.

2. In a low slugger for type slugs, a cutter, resilient means urging the cutter to retracted position, latch means normally latching the cutter in advanced position, trip means in advance of the cutter and engageable by type on the slug to release said latch means, and means operating with delayed action to advance the cutter and re-latch it upon the type passing the trip means.

3. In a low slugger for type slugs, a cutter, resilient means urging the cutter to retracted position, latch means normally latching the cutter in advanced position, trip means in advance of the cutter and engageable by type on the slug to release said latch means, said trip means including a switch and a electromagnet controlled thereby, and means including a mechanical time delay mechanism for advancing the cutter when the type passes the trip means.

4. In a low slugger for type slugs, a cutter, means including a control cam for latching the cutter in advanced position, means urging the cutter to a retracted position, means for releasing the latch and moving the cam to permit retraction of the cutter, and a delayed action mechanism operable by type on a slug for returning the cam to advance the cutter and re-latch it in its advanced position.

5. In a low slugger for type slugs, a cutter, means including a control cam for latching the cutter in advanced position, means urging the cutter to a retracted position, means for releasing the latch and moving the cam to permit retraction of the cutter, and a delayed action mechanism, including a slowly rotating ratchet disc and a pawl carried by the cam and engageable with the ratchet disc, for returning the cam to advance the cutter and re-latch it in its advanced position.

6. A time delay mechanism for a low slugging machine or the like, comprising a control cam mounted to rock on a pivot, a ratchet disc rotatable on an axis concentric with said pivot, means to latch the control cam in normal position, means to release the latch and rock the cam about its pivot, a pawl carried by the control cam and engageable with the ratchet disc only when the cam has been rocked from normal position, and means to rotate the ratchet disc for returning the cam to normal in a predetermined time.

7. A time delay mechanism for a low slugging machine or the like, comprising a control cam mounted to rock on a pivot, a ratchet disc rotatable on an axis concentric with said pivot, means to latch the control cam in normal position, means to release the latch and rock the cam about its pivot, a pawl carried by the control cam and engageable with the ratchet disc only when the cam has been rocked from normal position, means to rotate the ratchet disc for returning the cam to normal in a predetermined time, and means for releasing the pawl and re-latching the control cam upon return of the cam to normal.
